UNITED STATES PATENT OFFICE.

OTTIS M. MC GUIRE, OF BRIDGEPORT, NEBRASKA.

WHEEL-HOLDER FOR RAILWAY-CARS.

1,394,318.

Specification of Letters Patent. Patented Oct. 18, 1921.

Application filed June 24, 1921. Serial No. 480,084.

To all whom it may concern:
Be it known that I, OTTIS M. MC GUIRE, a citizen of the United States, residing at Bridgeport, in the county of Morrill, State of 5 Nebraska, have invented a new and useful 10 Wheel-Holder for Railway-Cars; and I do hereby declare the following to be a full, clear, and exact description of the invention, such as will enable others skilled in the art 15 to which it appertains to make and use the same.

The invention relates to wheel holders for railway cars, and has for its object to provide a device of this character adapted to be 20 secured to the journal box of a truck and extend upwardly and arch over the upper side of the truck wheel and form means whereby upon breaking of the journal within the journal box, the journal box will be 25 prevented from dropping downwardly into engagement with the cross ties of the railway and causing the car to be wrecked and cars following to be wrecked, said wheel being held in sliding engagement with the 30 rail by the wheel holder.

It has been found that where a journal becomes broken that sometimes the wheels become stuck, and the wheels will slide for miles on the rail without derailing the train, 35 therefore it is a further object to provide positive means for holding the wheel in engagement with the rail after the journal has become broken or burnt off.

With the above and other objects in view 40 the invention resides in the combination and arrangement of parts as hereinafter set forth, shown in the drawings, described and claimed, it being understood that changes in the precise embodiment of the invention 45 may be made within the scope of what is claimed without departing from the spirit of the invention.

In the drawing:—

Figure 1 is a side elevation of a railway 45 car truck showing the wheel holders applied thereto.

Fig. 2 is a perspective view of one of the wheel holders.

Referring to the drawings, the numeral 1 50 designates a truck beam, and 2 journal boxes carried thereby for the reception of journals 3 of the wheels 4 and in which

journal boxes the journals 3 are rotatably mounted and surrounded with lubricant. It has been found that the journals 3 at 55 times break or are burnt off, and under which conditions one of the ends 2 of the beam 1 drops and engages the road bed, particularly the cross ties and consequently the train is derailed, particularly the car 60 carrying the beam 1 the cars following. To overcome this difficulty and to provide means for holding the wheels 4 in slidable engagement with the treads 5 of the rails 6, wheel holders 7 are provided. Each wheel 65 holder 7 comprises a plate 8 secured as at 9 to the upper side of the journal box 2, and having upwardly extending diverging arms 10, the upper ends of which arms are provided with arched portions 11, which arch the 70 upper side 12 of the wheel and terminate in an arcuate connecting bar 13 which overlies the upper side 12 of the wheel. It will be seen that if the journal 3 becomes broken that the upper side 12, will when the journal 75 box 4 drops downwardly, be engaged by the arched portions 11 of the wheel holder 7, and that said wheel will be held in sliding engagement with the tread 5, thereby 80 preventing derailment, and at the same time allowing the train to be propelled in the usual manner to a place where the car with the broken journal may be repaired or replaced with a new car. It has been found that where the journals have been worn or 85 broken and the wheel becomes stuck in some manner with its tread in engagement with the tread of the rail, that the car may be moved for many miles by the wheel supporting the car and sliding on the rail. It will 90 be seen that the wheel holder will provide positive means for holding the wheel whereby it may be moved for great distances without danger. It will also be seen that the 95 device is simple in construction and so constructed that it may be easily and quickly applied to trucks now in use without modifying the construction of the truck.

The invention having been set forth what is claimed as new and useful is:—

A wheel and truck holding device of the character described, said device comprising a plate secured to the truck adjacent the journal box, said device having upwardly

and radially extending arms, the upper ends of said arms arching over the upper side of the wheel at spaced points from each other and a connecting bar connecting the ends of 5 the arched portions of the arms together, said bar being disposed on the opposite side of the wheel.

In testimony whereof I have signed my name to this specification in the presence of two subscribing witnesses.

OTTIS M. McGUIRE
